J. W. TAUSSIG

APPARATUS FOR BUILDING COMPOSITE PILES

Filed Feb. 17, 1926

UNITED STATES PATENT OFFICE.

JOHN W. TAUSSIG, OF ENGLEWOOD, NEW JERSEY, ASSIGNOR TO RAYMOND CONCRETE FILE COMPANY, OF NEW YORK, N. Y., A CORPORATION OF NEW JERSEY.

APPARATUS FOR BUILDING COMPOSITE PILES.

Application filed February 17, 1926. Serial No. 88,726.

This invention pertains to apparatus for making concrete piles of the composite type in which a concrete pile is superposed upon and united with a wooden pile in such manner that the concrete and wooden piles are formed into a unitary pile structure.

In one method of forming such composite piles it is customary to first drive the wooden pile until its head is at or near the ground level, then erect thereon a circumferentially corrugated tapered shell mounted on a non-collapsible corrugated core. The driving operation is then continued until the desired depth is reached, whereupon the driving core is removed, and the corrugated shell filled with concrete to form with the wooden pile the complete composite structure.

In order to remove the corrugated core from the corrugated shell it is necessary to unscrew the core from the shell a few turns before the core can be lifted out of the shell. By the time the driving of the pile is completed the shell is often very tightly pressed against the core by the surrounding earth and considerable force must be applied in order to effect the unscrewing operation.

It has been customary to turn the core by means of a worm and screw device at the head of the core, the turning reaction being taken by the leaders of the pile driver. This operation has thrown a great twisting strain on the leaders, especially when the top of the core is driven below the bottom of the leaders, in which event extensions must be attached to the leaders to take the strain.

The object of my present invention is to provide means for transmitting the turning reaction to the portion of the pile already driven and thus relieve the leaders of undesirable strain.

I am describing the lower portion of the composite pile as being of wood, as that is the usual construction, but it may be of concrete or other material. When I refer to the wooden pile I mean the pile first driven, and upon which is erected the shell in which the upper portion of the composite pile is formed. As stated above, the object of my invention is to remove from the leaders of the driving mechanism the rotative reaction of the core unscrewing device, by taking that

reaction on the pile first driven, which is well able to take the reaction as it is firmly set in the ground.

In the drawings,

Fig. 1 is a view, mostly sectional, showing a wooden pile and superposed corrugated shell at the completion of driving, with the corrugated core in driving position.

Fig. 2 is the same as Fig. 1 after the corrugated core has been unscrewed sufficiently from the shell so it may be lifted out.

Fig. 3 is an enlarged view, mostly in section, of one modification of the central column, showing details.

Fig. 4 is a view of another modification of the central column, showing an hydraulic device to hold the lower end of the column in engagement with the wooden pile.

Fig. 5 is a cross section on line 5—5 of Fig. 4.

Fig. 6 is a plan view of the core head, on line 6—6 of Fig. 2, showing worms and gears.

Fig. 7 is a section on line 7—7 of Fig. 2.

Fig. 8 is an enlarged detail of the top of the wood pile head in Figs. 1 and 2.

Fig. 9 is a top view of Fig. 8.

In Figs. 1 and 2 the wooden pile is designated 20. The upper end of pile 20 is reduced in diameter to form a tenon 22, and the hollow lower end of corrugated core 24 is fitted over the headed end 22 so that most of the driving effort is transmitted to the top of 22 by core partition 26.

The corrugated shell for the upper portion of the pile is designated 28.

Fast on the upper end of core 24 is worm gear 30, provided with lugs 29 fitted into sockets in the core to insure the core turning with the gear.

Core 24 is rotatably supported in head 32 by means of flange 34. Mounted for rotation in head 32 is shaft 36 on which is fast worm 31 in mesh with gear 30, so that when shaft 36 is turned core body 24 is rotated relatively to head 32.

Fitted into the top of head 32 is the threaded plug 38, which takes the driving effect from the hammer, the base of which is indicated at 40. The cables for supporting the core are shown at 42 and the wings

- 44 and 46 form guides on hammer and driving head respectively to cooperate with the leaders (not shown).
- Secured to the center of cap 38 by key 5 48 (Fig. 6) and depending therefrom axially within core 24 is the hollow column 50. Worm gear 30 and core 24 are mounted for rotation about the upper end of column 50, on bearing sleeves 52.
- 10 Column 50 terminates midway of the length of core 24, the lower end of the column being enlarged to form a shoulder or flange 54, in which are cut two diametrically opposite vertical key ways 56. Fitting 15 around flange 54 is a vertical cylinder 58, provided with two vertical splines 60 in the key ways 56. This construction permits cylinder 58 to slide vertically on flange 54 but prevents it from rotating relatively thereto.
- 20 Extending downwardly from the bottom of cylinder 58 is a stem 62, the lower end of which is anchored to the pile below it in the manner to be now described. Tenon 22 has a slot 64 (Fig. 8) cut across its top.
- 25 Set into the tenon, axially, below slot 64 is a bushing 66 having a threaded socket opening upwardly. Bushing 66 is held against rotation and withdrawal by a transverse pin 68 passing through tenon 22 and the lower 30 end of bushing 66. The lower end of stem 62 is enlarged to form a shoe or rectangular flange 100 (Fig. 4) which fits into slot 64 (Fig. 8) of tenon 22.
- The lower end of stem 62 is bored upward- 35 ly to form a cylindrical cavity 70, within which is supported the head 72 of threaded screw 74. The lower end of cavity 70 is closed by a threaded collar 76 having a hole in its center through which screw 74 pro- 40 jects downwardly and upon which the screw head 72 rests. Extending upwardly from head 72 is the square shank 78, and fitted over shank 78 is the key socket 80, the stem 82 of which extends upwardly through the center of stem 62 and column 50 until it terminates in worm gear 84 mounted for rotation in the center of driving plug 38 (Figs. 1, 2 and 6). Meshing with gear 84 is the worm 86 provided with shaft 88 extending to a 45 point outside the driving head.
- In operation, when the core and shell are assembled preparatory for driving, screw 74 is screwed into bushing 66 by means of the train of mechanism comprising shank 78, 50 key socket 80, key stem 82, worm gear 84, worm 86 and shaft 88. This locks the lower end of stem 62 into slot 64 of pile 20, prevents rotation of column 50 relatively to pile 20, and also prevents the withdrawal of 55 the shoe 100 on the lower end of stem 62 from slot 64. The parts are then in the position shown in Fig. 1, with flange 54 at the bottom of cylinder 58 and key socket 80 engaging the full length of shank 78 (Fig. 3).
- 60 After the composite pile is driven to the desired depth and it is desired to unscrew core 24 from shell 28 to the position shown in Fig. 2, so that the core may be lifted from the shell, worm gear 30 is rotated by means of worm 31 and shaft 36.
- During the unscrewing of core 24, head 32 is prevented from turning in the reverse direction to core 24 as follows: Slot 64 in pile 20 prevents stem 62 from turning, splines 60 in cylinder 58 prevent column 50 from turning, and key 48 prevents plug 38 and head 32 from turning, therefore all the reaction due to the unscrewing of core 24 is taken by the pile already driven.
- If there be danger of splitting the pile 70 tenon 22 due to excessive strain in slot 64 a steel band (not shown) may be placed around the upper end of the tenon.
- During the unscrewing operation the pile 75 core 24 rises, carrying with it the upper end 80 of column 50. As the lower end of column extension 62 remains in position, being fast to the wood pile, it is necessary to make column 62 automatically extensible in length. This is accomplished by the slip joint comprising cylinder 58 and flange 54 which permits the upper column 50 to rise relatively to stem 62, while preventing relative rotation as already explained. Cylinder 58 is 85 of sufficient length to permit the unscrewing of core 24 to the position shown in Fig. 2, in which its corrugations are entirely free of the corrugations in shell 28, thereby permitting the lifting of the core from the 90 shell by the hoisting tackle.
- Before the hoisting can take place, however, it is necessary to separate the lower end of stem 62 from slot 64 in the wooden pile. This is done by unscrewing screw 74 95 from bushing 66 with key socket 80, which is actuated by shaft 88 through worm gear 84 and key stem 82, as already explained.
- Screw shank 78 and key socket 80 are of sufficient length to prevent them coming out of engagement with each other when column 100 50 and stem 62 are extended to their full length as is the case when flange 54 is at the top of cylinder 58, as in Fig. 2.
- The upper end of cylinder 58 is closed by screw cap 90 to prevent flange 54 pulling 110 out of cylinder 58 during the unscrewing or lifting operation.
- In Fig. 4 is shown a modification of my invention in which I provide a hydraulic device to keep the lower end of stem 62 in engagement with the slot in the wooden pile, instead of the screw apparatus described above. In this modification a hydraulic cylinder 92 is placed below cylinder 58 and axially with it, the two cylinders being illustrated as separated by partition 94. A stem 96 is secured to the bottom of flange 54, extends through partition 94, and has on its lower end a plunger 98. The length of stem 96 is such that plunger 98 is at or near the 115 120 125 130

bottom of cylinder 92 when flange 54 is at or near the bottom of cylinder 58. Stem 62 extends downwardly from the bottom of cylinder 92 and has on its lower end a shoe 100 that engages slot 64 in the top of wood pile tenon 22.

Column 50 and stem 96 have a passage 102 throughout their length, and to the upper end of the passage is connected the discharge 104 of force pump 106, which is shown as a plunger pump provided with a manually operable handle 108, but which may be of any type capable of providing sufficient pressure, and it may be operated by power if desired.

In operation, during the unscrewing of core 24 from shell 28, pump 106 is operated to keep the space below plunger 98 filled with oil, water, or other liquid 110, at sufficient pressure to overcome the friction of flange 54 in cylinder 58 and thereby maintain shoe 100 fully engaged with slot 64 in the wood pile.

At the completion of the unscrewing of core 24 from shell 28 cylinder 92 may be full of oil 110. Before engaging the next pile the connections to the pump are reversed and the oil is forced back through the pump to the oil reservoir, and the apparatus is again ready for use.

To assist in preventing shell 28 turning in the ground while the core is being unscrewed, projecting fins 112 are attached at intervals to the outer surface of the shell. During the unscrewing operation the hollow central portion of core 24 is sometimes filled with water, air, or other fluid under pressure. The fluid passes through openings 114 into the space between core and shell and, spreading between the surfaces, helps to reduce the friction between them, and decrease the effort required to effect the unscrewing operation.

I have illustrated and described only preferred forms of my invention, but the invention may be embodied in modifications which vary in detail from the structure or method herein shown without departing from the spirit of the invention.

50 I claim—

1. In an apparatus for forming and driving composite piles, comprising wooden piles surmounted by corrugated concrete piles, in combination, a shell corrugated in screw thread fashion, a driving core provided with screw thread corrugations cooperating with the corrugations in the shell, means to unscrew said core from said shell after driving, and means to transmit the reaction of said unscrewing operation to the wooden pile.

2. In an apparatus for forming and driving composite piles, comprising wooden piles surmounted by corrugated concrete piles, in combination, a shell corrugated in screw thread fashion, a driving core mounted for

rotation on a central member and provided with screw corrugations to cooperate with the corrugations in the shell, means to apply force tending to rotate said core on said central member, said central member transmitting the reaction of said force to the wooden pile.

3. In an apparatus for erecting composite piles, comprising wooden piles surmounted by concrete piles, in combination, a driving core, means to apply force to rotate said core, and means to transmit the reaction of said force to the wooden pile.

4. In an apparatus for erecting composite piles comprising wooden piles surmounted by concrete piles, in combination, a driving core mounted for rotation on a central member, means to apply force to rotate said core on said central member, said central member being arranged to transmit the reaction of said force to said wooden pile.

5. In an apparatus for erecting composite piles, comprising wooden piles surmounted by concrete piles, in combination, a shell, a driving core within the shell, means to apply force to rotate said core relatively to said shell, and means to transmit the reaction of said force to the wooden pile.

6. In an apparatus for erecting composite piles comprising wooden piles surmounted by concrete piles, in combination, a shell, a driving core mounted for rotation on a stationary member, means to apply force to rotate said core on said member, said member being arranged to transmit the reaction of said force to said wooden pile.

7. In an apparatus for erecting composite piles comprising wooden piles surmounted by concrete piles, in combination, a driving core, means to apply force to rotate said core and a stationary structure engaging said wooden pile to take the reaction of said force.

8. In an apparatus for erecting composite piles comprising wooden piles surmounted by concrete piles, in combination, a core mounted for rotation on a central member, means to maintain said member in engagement with the wooden pile, and means to apply force to rotate said core on said member, the reaction of said force being taken by said central member.

9. In an apparatus for erecting composite piles comprising wooden piles surmounted by concrete piles, in combination, a core mounted for rotation on a central member, means comprising a screw to maintain said member in engagement with the wooden pile, and means to apply force to rotate said core on said member, the reaction of said force being taken by said central member.

10. In an apparatus for forming and driving composite piles, comprising wooden piles surmounted by corrugated concrete piles, in combination, a shell corrugated in screw thread fashion, a driving core mounted for

rotation on a central member and provided with screw corrugations to cooperate with the corrugations in the shell, a telescopic device to lock said central member to the 5 wooden pile to prevent rotation of said central member, and means to rotate said core on said central member.

11. In an apparatus for forming and driving composite piles, comprising wooden piles 10 surmounted by corrugated concrete piles, in combination, a shell corrugated in screw thread fashion, a driving core mounted for

rotation on a central member and provided with screw corrugations to cooperate with the corrugations in the shell, a telescopic 15 device hydraulically operable to lock said central member to prevent rotation thereof relatively to the wooden pile, and a device to rotate said core relatively to said central member.

In testimony whereof I hereto affix my signature.

JOHN W. TAUSSIG.
